[57] CLAIM

The ornamental design for an idler for a low profile tie down, substantially as shown.

DESCRIPTION

FIG. 1 is a perspective view of an idler for a low profile tie down, showing my new design;
FIG. 2 is a right side elevational view thereof;
FIG. 3 is a front elevational view thereof;
FIG. 4 is a bottom plan view thereof;
FIG. 5 is a rear elevational view thereof.

FIG. 1

FIG. 2

FIG. 3

FIG. 4

FIG. 5
